UNITED STATES PATENT OFFICE.

EARL W. LESHER, OF CLEVELAND, OHIO.

SHINGLE.

1,425,991.

Specification of Letters Patent. Patented Aug. 15, 1922.

Application filed December 6, 1920. Serial No. 428,546.

To all whom it may concern:

Be it known that I, EARL W. LESHER, a citizen of the United States, residing at Cleveland, in the county of Cuyahoga and State of Ohio, have invented certain new and useful Improvements in and Relating to Shingles, of which the following is a specification.

This invention relates to a roof, more particularly to the shingles therefor.

One object of the invention is to provide a plurality of shingles for roofing purposes having along adjoining edges interlocking devices, whereby they may be rapidly laid in spaced and aligned relationship.

Another object of the invention is to provide a shingle which is so cut along its opposite sides that it may be spaced from and align with another shingle or shingles of like construction to form a durable roof covering.

A further object of the invention is to provide a shingle having along its opposite side edges complimentary walls permitting the shingles to be cut from a strip of material without waste and correlated economically in spaced and aligned arrangement.

Other objects of the invention will be apparent to those skilled in the art to which my invention relates from the accompanying drawings taken in connection with the following description.

In the drawings, Figure 1 is a perspective view of a shingle embodying my invention and made according to my improved process.

Fig. 2 is a plan view of a plurality of shingles showing them arranged side by side and in spaced and aligned relationship.

Fig. 3 shows a portion of a roof covered with shingles embodying my invention.

Fig. 4 is a top plan view of a roll of material, partly broken away, showing a portion extended and a set of shingles embodying the form of construction shown in Figs. 1, 2 and 3, cut therefrom.

Fig. 5 is a perspective view of a shingle showing a slightly modified form of my invention.

Fig. 6 is a plan view of a plurality of shingles embodying the invention shown in Fig. 5, arranged side by side in spaced and aligned relationship.

Fig. 7 is a fragmentary view of a roof

formed by shingles of the type shown in Figs. 5 and 6.

Fig. 8 is a fragmentary view corresponding to Fig. 4, showing the manner of cutting a set of shingles of the form shown in Figs. 5, 6 and 7.

In the drawings, 1 indicates as an entirety a plurality of shingles adapted to be arranged side by side and overlapping in the usual way, as shown in Fig. 3, to form a roof or roof covering. Each shingle may be stamped out of suitable material, such as asphalt or composition, by a suitable die, but in carrying out my improved process, for economical reasons, I cut the shingles from an endless strip or roll A of asphalt, as will be understood from Fig. 4. When made in this last referred to manner, I am enabled to avoid all waste of material (except a small portion of the outer shingles of each set along one edge of the outermost shingles equal to the length of the longest projecting member to which reference will later be made) and at the same time to so cut the strip of material that the interlocking devices on one edge of each shingle may be correlated with the interlocking devices of the opposite edge of the adjacent shingle to space and align the shingles parallel relative to each other.

To prepare the strip A for use in carrying out my process, I first cut the free edge of the strip A along a broken line B to form three offsets b each spaced from the adjacent side edge of the strip or the adjacent offset of the next shingle a distance equal to the width of a shingle, allowance being made for the projecting members along the outer end shingles. In my process I prefer to first cut the strip A on longitudinal broken lines C, coinciding with the side wall of each offset b and inwardly equal distances and to then cut the strip on the transverse lines D, D, to complete the cutting out of the shingles and sever them from the body of the strip A. It will be understood, however, that these steps or operations may be reversed. As shown, I am enabled to provide four shingles from a single width of material. These operations are continued until the strip is entirely cut.

Each longitudinal cut is arranged to form a plurality of projecting members on one edge of each shingle and corresponding re-

cesses on the opposite edge thereof. In the form of construction shown in Figs. 1, 2 and 3, I cut the strip to provide three projecting members 2, 3 and 4 in one edge of each shingle 1, one of which is longer than the remaining members, thereby forming in the adjoining edge of each adjacent shingle correspondingly shaped recesses 2', 3' and 4'. To avoid having the longest projecting member or members (which in the present form of construction are designated 3 and 4) extend too far beyond the edge of the shingle and thereby be objectionable for shipping purposes, I prefer to extend the broken lines of the longitudinal cut to either side of a line, coinciding with the offset b , on which the longitudinal cut is made. In this arrangement, it will be seen that the projecting member 2 does not project beyond the cutting line; it will also be understood that those portions of the material which constitute the walls of the recess 2' formed by the projecting member 2, project beyond the side edge of the shingle when it is cut, as shown at 5, 6. By this construction, that portion of the material necessary to form the projecting members to secure proper spacing and alignment is divided, instead of all being on one side of each shingle.

When the shingles are laid side by side on the structure to be covered, the projecting member 3 on one edge of each shingle is positioned in the recess 2' of the adjacent edge of the adjoining shingle, such interlocking insuring alignment of the upper and lower edges of the shingles, one with another. To insure this arrangement the broken lines of each longitudinal cut are correlated to arrange the projecting member 3 a distance from the recess 2' equal to the length of the offset b , so that when the shingles are laid on a structure or roof, the projecting member 3 will engage the recess 2' and thus serve as guiding devices whereby the workman can readily align the shingles in rows. It will be seen that the projecting member 3 and recess 2' serve as interlocking devices to hold the shingles in aligned relationship. As shown in Figs. 2 and 3, when the shingles are aligned and locked, the projecting member 4 will engage the side edge of the adjacent shingle and in co-operation with the projecting member 3 serve to space the shingles in parallel relationship.

The interlocking devices 3, 2', may be arranged near the upper ends of two shingles and the spacing member 4 may be arranged below them. However, I prefer to arrange these interlocking devices so that they will be disposed below the upper edges of the shingles in the next lower row, as it permits each shingle 1 to be laid on the next lower row of shingles and moved in the plane of the adjacent shingle to cause interlocking

of the devices 3, 2', without danger of the projecting member being pressed below and under the edge of the adjacent shingle, which might result if the interlocking devices were arranged near the upper edge of 70 the shingles.

It will be seen that the projections serve as self-spacing devices between the shingles so that they may be free to expand and contract due to the elements. In carrying out 75 my invention I am enabled to reduce the contacting surfaces to a minimum by tapering the projections, thus forming substantially point contacts and minimum material to be affected by the elements. This will be 80 understood from the drawings, since the tapered points of the projecting members 2 and 4 will yield when expansion takes place without affecting the body portion of the shingle.

In Figs. 5, 6, 7 and 8 I have shown a modified form of construction wherein the shingles are provided with two sets of interlocking devices both of which serve to space and align the shingles relative to each other. 90

In these views, 7 indicates the shingles which may be cut from a strip A' according to my process which has already been described. In making the longitudinal cuts in this form of construction, I provide two 95 projecting members 8, 9, of equal length and two projecting members 10, 11, of equal length, but longer than the members 8, 9, preferably by a distance equal to the space to be provided between adjacent shingles. 7 100 (see Fig. 6). In providing these projecting members 8, 9, 10, 11, I form correspondingly shaped recesses 8', 9', 10', 11', respectively, in the adjoining edge of the adjacent shingle. In laying the shingles 7, 105 the projecting members 10, 11, are positioned in the recesses 8', 9', respectively. As the projecting members 8, 9, are spaced from the projecting members 10, 11, respectively, a distance equal to the length of the offset 110 in the transverse cut B' at the end edges of adjacent shingles (see Fig. 8), it will be seen that the interlocking devices 8', 9', 10 and 11 serve to space the shingles in parallel relationship and also to align their upper and 115 lower end edges.

The projecting members 8, 9, 10 and 11 are tapered so that when the members 10, and 11 fit into the recesses 8', 9' respectively, the contacting surface between adjacent 120 shingles is reduced to a minimum for reasons already set forth in connection with the shingles shown in Figs. 1 to 4, inclusive. In cutting the projecting members 8, 9, 10 and 11, I prefer to make their lower walls 125 horizontal, whereby the projecting members 10 and 11 will rest upon the lower wall of the recesses 8', 9' respectively. I also prefer to arrange the walls of each projecting member 8, 9, at an angle relative to each 130

other that is less acute than the angle between the walls of each projecting member 10 and 11. When so arranged, it will be seen that no contact occurs between the upper 5 per wall of each projecting member 10, 11, with the upper wall of the adjacent recesses 8', 9', respectively.

From the foregoing description, it will be seen that I have provided a shingle which 10 can be readily made in a rapid manner from a continuous or endless strip of material without waste of material. I am also enabled to provide shingles which are self-spacing and self-aligning, permitting laying 15 thereof in a rapid manner. I am also enabled to provide roof shingles so constructed that minimum contact is required between them, thereby obviating objections due to expansion and contraction of the 20 shingles. The aligning and spacing devices serve to close the space between adjacent shingles to prevent wind from getting in underneath the superposed rows of shingles.

It will also be seen that in carrying out 25 my process I am enabled to so cut the shingles that they are duplicates of each other, which permits them to be readily stacked or packed and shipped, and at the same time readily provide the necessary 30 spacing and aligning devices.

To those skilled in the art of making devices of the class described, many alterations in construction and widely differing embodiments and applications of my invention will 35 suggest themselves, without departing from the spirit and scope thereof. My disclosures and the description herein are purely illustrative and are not intended to be in any sense limiting.

40 What I claim is:

1. A shingle having along one edge a plurality of spaced projecting members of different lengths and along its opposite edge a recess, said recess being arranged in transverse alignment with said longer projection of said shingle and adapted to receive the longer projection on a similarly shaped shingle when it is correlated therewith.

2. A shingle having along one edge a plurality of projecting members of different lengths and along its opposite edge complementary recesses disposed in longitudinal off-set relation to said projecting members so that when the longer projecting member of 55 the shingle is inserted in a recess of another shingle other than the one which is complementary to the longer projecting member, the shingles will be spaced relative to each other.

60 3. A shingle having along its opposite edges sets of complementary projecting members and recesses, each recess being off-set longitudinally relative to its corresponding projecting member so that when the shingle 65 is correlated adjacent to another shingle one

of said projecting members interlocks with a recess complementary to another projecting member to effect alignment of the shingles.

4. A shingle provided along one edge with 70 a plurality of projecting members of different lengths and formed along its opposite edge with recesses, one of said recesses being of less depth than the length of the longer projecting member of said shingle 75 and arranged to receive the longer projecting member of another shingle when the latter is correlated therewith.

5. A shingle provided along one edge with 80 a plurality of tapered projecting members of different lengths and formed along its opposite edge with a recess, said recess being of less depth than the length of the longer projecting member of said shingle and shaped to receive the longer projecting member 85 of another shingle when the latter is correlated therewith.

6. A shingle having one edge provided with a series of alternately arranged long and short projecting members and having 90 its opposite edge formed with a series of similarly arranged and shaped recesses arranged out of transverse alignment with their complementary projecting members, respectively, whereby each longer projecting member on one edge of the shingle is adapted to be inserted in the recess of another shingle corresponding to a shorter projecting member when the latter is correlated therewith to space and align said 100 shingles relative to each other.

7. A shingle having one edge provided with a series of alternately arranged long and short projecting members and having 105 its opposite edge formed with a series of similarly arranged and shaped recesses arranged out of transverse alignment with their complementary projecting members, respectively, whereby each longer projecting member on one edge of the shingle is 110 adapted to be inserted in the recess of another shingle corresponding to a shorter projecting member when the latter is correlated therewith to space and align them 115 relative to each other, the lower walls of each projecting member and recess being horizontal.

8. A shingle having one edge provided with a series of alternately arranged long and short projecting members and having 120 its opposite edge formed with a series of similarly arranged and shaped recesses arranged out of transverse alignment with their complementary projecting members, respectively, whereby each longer projecting member on one edge of the shingle is 125 adapted to be inserted in the recess of another shingle corresponding to a shorter projecting member when the latter is correlated therewith to space and align them 130

relative to each other, the walls of each recess corresponding to a short projecting member being arranged at an angle less acute than the walls of each longer projecting member.

9. In a roof or covering, the combination of a plurality of similarly shaped shingles each having along its opposite edges projecting members and complementary recesses, said projecting members and recesses of each shingle being arranged out of transverse alignment, respectively, and so constructed that when two shingles are laid side by side said projecting members and recesses therebetween will co-operate as spacing and aligning devices for said shingles.

10. A shingle having along one edge projecting members of different lengths, and along its opposite edge recesses similar in shape and size to said members but in transverse disalignment therewith, respectively, equal to the distance between corresponding end walls of said projecting members.

11. A shingle having along one edge a pair of projecting members of different lengths and formed along its opposite edge with a recess adapted to receive the longer

projecting member on a similarly shaped shingle when it is correlated therewith, said recess having a depth equal to the length of the longer projecting member less the length of the shorter projecting member, whereby the shorter projecting member will engage the edge of the adjacent shingle and co-operate with the longer projecting member to space the shingles in parallel relationship.

12. A shingle provided along one side edge with projecting members of different lengths and formed along its opposite side edge with correspondingly shaped recesses arranged in transverse disalignment with said projecting members, respectively, so that when another shingle is correlated with said shingle the engagement of its longer projecting member with the wall of the recess of said shingle corresponding to the short projecting member and the engagement of its short projecting member with the side edge of said shingle will serve to space and align the shingles.

In testimony whereof I affix my signature.

EARL W. LESHER.
